EMBORESSED PICTURE AND METHOD OF PRODUCING IT

Sydney Hayden, Hampstead, London, England

Application June 20, 1934, Serial No. 731,516
In Great Britain June 7, 1934

8 Claims. (Cl. 41—24)

This invention relates to embossed pictures and method of producing them, and more particularly to the method in which a sheet of ductile metal or metal foil is embossed to bring out in relief selected features of a photograph or picture printed on the sheet of metal or foil and the sheet backed with a substance moulded in situ.

According to the present invention the substance with which the ductile or foil sheet is backed is cast or moulded into a frame to which the said sheet is permanently secured.

In carrying the preferred form of this invention into practice a wooden or other suitable rigid frame has laid upon it a sheet of ductile metal or metal foil, said sheet being of such dimensions that it overlaps all or the majority of the edges of the frame. Upon the sheet is reproduced a photograph and the photograph is brought out into the desired relief by tooling the sheet to produce ridges and arcuate mounds and recesses therein. The marginal parts of the sheet which overlap the frame are folded over the edges of the frame on to the back of the frame, the corners of the sheet if necessary being cut to permit of such folding. A suitable filling material such as for example a quick setting gypsum plaster or a cement is deposited in the frame so as to fill up the space inside the frame behind the metal or foil sheet up to the level of the folded over ends of the sheet where they lie against the back of the frame, a suitable straight edge levelling off the filling substance to enable a suitable back plate or panel of wood or other suitable material to be laid flush against the said folded over marginal part of the metal or foil sheet. By driving wood screws or nails through the said back plate into the said frame a solid assembly is provided in which the boundary edges of the finished plaque are composed of the metal sheet or foil. By pressing in the said sheet along lines bounded by the inner edges of the said frame during the tooling or embossing operation an effect of a solid metal outer frame can be obtained the effect being enhanced by having a definite boundary or demarcation line for the picture or photograph at the folds or creases of the thin metal or foil sheet extending along the inner edges of the frame.

A method of and means for carrying the invention into effect is shown in the accompanying sheet of drawing, wherein:—

Fig. 1 is a sectional view showing the thin metal or foil sheet with the frame on to which it is to be secured laid thereon.

Fig. 2 is a sectional view showing the thin metal

or foil sheet folded at its marginal parts over the edges and back of the said frame.

Fig. 3 is a sectional view showing the said sheet uppermost and a picture marginal embossing or recess being formed.

Fig. 4 is a sectional view showing the picture being embossed.

Fig. 5 is a sectional view showing the backing filled into the frame upon the said sheet, and

Fig. 6 is a sectional view showing the back plate 10 or panel secured to the finished plaque.

Referring to the drawing a thin sheet 1 of ductile metal or metal foil has printed on one face a photograph or picture for which purpose the sheet may be coated on one surface with a suitable sensitive emulsion such as for example a mixture of gelatine and chrome alum. The picture to be embossed can be printed on the sensitized surface and developed. Upon the opposite side of the sheet is applied a coating of cellulose 20 or other suitable material which will adhere tenaciously to the sheet. Sand or other gritty material is incorporated with this coating to provide a roughened surface whereby plaster or a plastic composition will adhere firmly to the back of the sheet. The back of the sheet has laid upon it a rectangular or other suitably shaped wooden frame 2, the arrangement being that preferably all of the edges of the sheet 1 extend beyond the outer edges of the frame 2 thereby 30 providing a surrounding margin 3 which as shown in Fig. 2 is folded over the outer edges and rear face of the frame 2. This provides a surround or edge which gives a thick metal effect.

The appearance of solidity is enhanced by 35 forming in the front face of the sheet 1 parallel with its outer edges a depression 4 extending completely around the sheet parallel with the sides of the frame 2. This is effected by applying pressure by means of a finger or tool as indicated at 5 in Fig. 3, the finger or tool being slid along and across the sheet 1 and guided by the inner edge of the frame 2.

The next operation is to manipulate the taut sheet 1 by a tool 6 and/or finger from both sides 45 to produce the desired contours and ridges or grooves in the sheet 1, the parts selected for example being the profile of a photograph of a face, the ears and cheek, etc. The back of the sheet is coated with cellulose or other suitable material and sand or other gritty material is embedded in this coating. The device is now ready for pouring in a suitable setting material which will harden in the frame 2 and will flow 50 in the crevices formed in the rear face of the 55

sheet 1. The setting material 9 which may be plaster of Paris, cement or the like is levelled off as shown in Fig. 5 to the same plane as the outer faces of the marginal parts 3 where they are 5 folded against the rear face of the frame 2. By this means a level plane is provided against which is laid a panel 7 of wood, sheet metal or other suitable material (see Fig. 6) which overlaps the rear folds of the marginal parts 3 of the sheet 10. Wood screws 8 or other suitable fastening members are driven through the back panel 7 into the frame 2 so that the filling substance 9 is obscured.

The sheet 1 can be slit or cut away at the corners or bends of the frame 2 to facilitate folding over of the sheet material. The coating of the back of the sheet 1 with cellulose and sand can be effected after the frame 2 is laid against the sheet 1 so that the marginal part 3 of the sheet 1 will have a smooth close fit against the frame 2. Alternatively if a rough stipple or "unfinished casting" effect is required the marginal part 3 can be coated on its inner face. It is preferred to allocate a picture or photograph 25 area to the sheet 1 corresponding to the internal dimensions of the frame 2 so that the part of the sheet 1 which lies against the frame 2 has a definite line of demarcation from the photograph or picture and can be polished to show a clean metal surface imparting the effect of a thick metal frame or surround. The finished picture may be sprayed or otherwise coated with cellulose or other lacquer to form a protective surface. The back of the panel 7 can be fitted 30 with a hinged strut 10.

I claim:—

1. An embossed picture comprising a frame, a sheet of thin metal laid against one face of the frame, a picture on said sheet, depressions 40 and ridges formed in said sheet, a marginal extension of said sheet completely overlapping the edges of said frame and folded against the rear face of said frame, and a backing substance moulded into the said frame and solidified.

2. An embossed picture comprising a frame, a sheet of thin metal laid against one face of the frame, a picture on said sheet, depressions and ridges formed in said sheet, a marginal extension of said sheet completely overlapping the edges of said frame and folded against the rear face of said frame, and a backing substance moulded into the said frame and solidified, said backing substance being moulded into the frame so as to fill the frame and to be flush with the rear outer face of said marginal extension at the rear of the frame.

3. An embossed picture comprising a frame, a sheet of thin metal laid against one face of the frame, a picture on said sheet, depressions and ridges formed in said sheet, a marginal extension of said sheet completely overlapping the edges of said frame and folded against the rear face of said frame, a backing substance moulded

into the said frame and solidified, and a back panel secured to the said frame, the edges of the said sheet lying between said panel and said frame.

4. An embossed picture comprising a frame, a sheet of thin metal laid against one face of the frame, a picture on said sheet, depressions and ridges formed in said sheet, a marginal extension of said sheet completely overlapping the edges of said frame and folded against the rear face of 10 said frame, and a backing substance moulded into the said frame and solidified, said sheet being formed with a depression extending along the sheet inside and parallel with the inner edges of said frame.

5. An embossed picture comprising a frame, a sheet of thin metal laid against one face of the frame, a picture on said sheet, depressions and ridges formed in said sheet, a marginal extension of said sheet completely overlapping the 20 edges of said frame and folded against the rear face of said frame, and a backing substance moulded into the said frame and solidified, a back panel secured to the said frame, the edges of the said sheet lying between said panel and 25 said frame, said sheet being formed with a depression extending along the sheet inside and parallel with the inner edges of said frame.

6. Method of producing an embossed picture consisting in mounting a sheet of thin ductile 30 metal or metal foil on a frame, forming a picture on said sheet, embossing the said sheet to bring parts of the picture into relief, coating the back of the sheet with cellulose or other coating and sand or other gritty material, and pouring a 35 moulding material into the said frame so that it adheres to the back of the sheet and solidifies in the frame.

7. Method of producing an embossed picture consisting in providing a frame, laying a sheet of thin ductile metal or foil on said frame, forming a picture on said sheet, folding the edges of said sheet over the outer edges and rear face of said frame, embossing the sheet to the desired contours, moulding into said frame against the back 40 of said picture a composition which solidifies in the frame, and applying a back panel over the frame covering the edges of the said sheet.

8. Method of producing an embossed picture consisting in providing a frame, laying a sheet 50 of thin ductile metal or foil on said frame, forming a picture on said sheet, folding the edges of said sheet over the outer edges and rear face of said frame, embossing the sheet to the desired contours, forming depressions in the front face of said 55 sheet parallel with and guided by the inner edges of said frame, moulding into said frame against the back of said picture a composition which solidifies in the frame, and applying a back panel over the frame covering the edges of the said 60 sheet.

SYDNEY HAYDEN.
